R. C. Adams

UNITED STATES PATENT OFFICE.

THOMAS ADAMS, OF SHEBOYGAN, WISCONSIN.

SAFETY DEVICE FOR WRINGERS.

Application filed February 12, 1927. Serial No. 167,801.

This invention relates to a safety attachment for clothes wringers, the general object of the invention being to provide means for preventing the fingers of the operator 5 from getting between the rolls of the wringer.

Another object of the invention is to provide means for causing the clothes to pass to the rolls of the wringer as they are placed 10 in the attachment.

A still further object of the invention is to provide means whereby the device can be easily and quickly attached to the wringer.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several views, and in which:—

Figure 1 is a perspective view showing the invention attached to a wringer.

Figure 2 is an elevation of the attachment.

Figure 3 is a plan view thereof.

Figure 4 is a view of the inner end of the attachment.

Figure 5 is a section on line 5—5 of Figure 2.

As shown in these views, the attachment is 35 of trough shape and comprises the bottom piece 1, and the side pieces 2, these pieces being suitably connected together and the bottom piece 1 curves upwardly from a flat 40 inner part and extends beyond the outer ends of the side pieces 2, with its extremity bent upon itself to produce the roll 3 at the outer end of the device. This roll is arranged on top of the bottom piece. Strips 4 are 45 fastened to the inner ends of the side pieces

2 and these strips have their upper ends bent into hook shape, as shown at 5, so that these strips can engage the end pieces of the wringer A, as shown in Figure 1.

From the foregoing, it will be seen that 50 the attachment can be easily and quickly placed on a wringer and when in position it is simply necessary to place the clothes on the curved portion of the device, when they will slide down the same against the rollers which will grip portions thereof and thus draw the clothes through the wringer. The roll 3 acts to guide the clothes as they are brought up out of the washing machine or tub and it is not necessary to use the 55 hands to feed the clothes between the rollers so that there is no danger of the operator being injured by having his hands caught between the rollers of the wringer.

The drawings show the device applied to 60 an electrically operated wringer, but, of course, it could be applied to any kind of a wringer.

It is thought from the foregoing description that the advantages and novel features 70 of my invention will be readily apparent.

I desire it to be understood that I may make changes in the construction and in the combination and arrangement of the several parts, provided that such changes fall within the scope of the appended claim.

What I claim is:—

An attachment for a wringer comprising a trough-shaped member having the inner portion of its bottom flat and the outer portion curving upwardly and outwardly, the outer end of the bottom part extending beyond the side pieces of the trough and having its extremity bent upon itself to provide a roll at the outer end of its top face and a 80 hook at the inner end of each side piece for engaging the upper ends of the end pieces of a wringer.

In testimony whereof I affix my signature.

THOMAS ADAMS.
